UNITED STATES PATENT OFFICE.

WILLIAM BREWSTER CHAPMAN, OF NEW YORK, N. Y., ASSIGNOR TO CHAPMAN ENGINEERING CO., OF NEW YORK, N. Y., A CORPORATION OF NEW YORK.

GAS-PRODUCER.

1,165,569.

Specification of Letters Patent. Patented Dec. 28, 1915.

Application filed February 26, 1912. Serial No. 679,863.

To all whom it may concern:

Be it known that I, WILLIAM B. CHAPMAN, a citizen of the United States, and a resident of the city of New York, borough of Manhattan, county and State of New York, have invented certain new and useful Improvements in Gas-Producers, of which the following is a full, clear, and exact description.

10 My invention relates especially to gas producers wherein there is a rotating body section surrounding the ash zone, and the object of the invention is to effect the ready and preferably automatic removal of the 15 ash from the pit or other part of the producer in which the ash accumulates.

To this end my invention involves certain novel features of construction and combination and arrangement of parts, all of 20 which will be fully set forth hereinafter and particularly pointed out in the claims.

For the purpose of a detailed description of my invention, reference is now had to the accompanying drawings, which represent, as an example, the preferred embodiment of the invention.

In these drawings—Figure 1 is a section of a plan view of so much of the producer as concerns my present invention; Fig. 2 is a detailed section on the line 2—2 of Fig. 1; Fig. 3 is a detailed section on the line 3—3 of Fig. 1; Fig. 4 is a side elevation of the ash plow as shown in Fig. 3; and Fig. 5 is a fragmentary elevation 35 particularly showing the dip in the ash shelf.

My present improvements relate exclusively to the disposal of the ashes. I have confined the drawings to these features and 40 illustrated only fragments of the producer, according to which 10 is a part of the rotating section of the producer which encloses the ashes, and 11 is the usual ash pit or foundation receiving the ash from the 45 section 10 and flooded with water to quench the ashes and seal the producer.

My present invention has to do with the devices for removing the ashes from the pit 11.

50 The ashes falling by gravity and under the weight of the contents of the producer lie in the pit 11 on the angle of repose from the lower end of the producer section 10. The problem is to remove the ash outward and upward of said pit. According to this,

I employ a plow 12 in the form of a blade with its tongue 13 mounted to twist in a bearing 14, attached to the lower portion of the producer section 10. This plow 12 projects downward to the pit 11 and is rotatable in its bearing 14 so that its angularity to the line of travel may be regulated. For this purpose a handle 15 is attached to the tongue 13, the handle coating with a toothed quadrant 16 to hold the handle and hence the plow in any desired adjustment. The plow 12 in thus sweeping through the body of ash in the pit 11 will form a cleft therein. Ordinarily, the ash would tumble back into this cleft equally from both sides, but owing to the pressure of the fuel bed within the producer, the ash will fall outward much in excess of the inward falling motion. The result therefore is a continued outward and upward movement of the ash 75 in the wake of the plow. This effect may be enhanced by adjusting the angularity of the plow to its line of travel, so that it tends to thin the ash outward in addition to and independently of the natural falling tendency above referred to; and it is further enhanced by the sloping inner wall of the pit 11 (see Fig. 2).

By these means, therefore, a continued movement of the ash outward and upward 85 from the lower edge of the producer section 10 is brought about, and it is necessary to remove the ash from the outer portion of the pit 11 over and beyond the top edge thereof. This is effected by a shelf 17, which is in 90 the form of a plate horizontally-disposed and attached to the producer section 10 to travel therewith between said section and a top edge of the pit 11, as shown in Fig. 2. The leading edge of this shelf dips downward below said top edge of the pit 11 in the manner shown in Fig. 5. The result of this is that as the ash shelf sweeps with the section 10 through the pit 11, a quantity of ash is steadily scooped up by and on the 95 shelf. The quantity of ash thus deposited on the shelf 17 depends upon the quantity forced outward and upward by the plow 12, and this in turn depends, as I have pointed out, upon the adjustment of the plow.

For removing the ash automatically from the shelf 17 as it accumulates thereon, I employ a scraper 18. This is in the form of a flat bar or plate, disposed on edge immediately over the plane of the high part of 110

the shelf 17. Preferably the said bar 18 is mounted in a suitable stationary support 19 by a pivot 20 at one end and its free outer end is held yielding toward the center of the 5 producer by a spring 21. The rear of the following edge of the ash shelf is cut off diagonally as shown in Fig. 1 and is furnished with a vertical lip or guide 17^a, against which the free inner end of the 10 scraper 18 runs when the scraper and ash shelf are in contact. Accordingly, in the operation of the producer, as the section 10 rotates, the plow steadily throws the ash outward toward the pit 11 and the ash shelf 15 17^a as steadily scoops up the ash which is thereby piled on the shelf. Periodically the ash shelf runs under the scraper 18, and this, striking the lip 17^a, throws from the shelf the accumulated ash. During this 20 operation, the scraper 18 swings outward, to permit the lip 17^a to pass, after which the spring 21 returns the scraper to its inward position preparatory to a repetition of the operation. The ashes being thus thrown 25 forward beyond the pit 11 may be disposed of manually or otherwise as desired.

What I claim is:

1. A gas producer having a traveling shelf or scoop arranged to move over a body of 30 ash to scoop or skim off the upper part thereof, and means coacting with the said shelf or scoop periodically to sweep or throw the ashes from the same.

2. A gas producer having means for automatically raising or elevating a body of ash, a traveling shelf or scoop arranged to move 35 over said body of ash to scoop or skim off the upper part thereof, and means coacting with said shelf or scoop periodically to sweep or throw the ashes from the same.

3. A gas producer having a traveling shelf or scoop arranged to move over a body of ash to scoop or skim off the upper part thereof, and a relatively stationary sweeper 40 or scraper under which the said shelf or scoop periodically runs, whereby the ashes are swept or thrown from the shelf.

4. In a gas producer the combination of a

traveling shelf or scoop adapted to move over a body of ash to scoop or skim off the 50 upper part thereof, and a swinging scraper mounted independently of the said shelf or scoop and adapted periodically to sweep over the same for the purpose specified.

5. In a gas producer the combination of a 55 traveling shelf or scoop adapted to move over a body of ash to scoop or skim off the upper part thereof, a diagonal wall on said shelf and a swinging scraper mounted independently of the shelf but in the path thereof 60 and adapted to be engaged by the said diagonal wall for the purpose specified.

6. In a gas producer the combination of a stationary ash pit, a rotating producer section extending into the same, an ash plow 65 carried by such section and serving to work the ashes onward and upward in the outer part of the pit, a shelf or scoop traveling with the producer section outside thereof, to scoop or skim off the upper part of the ashes 70 in the pit, and a scraper past which the shelf or scoop periodically moves to throw or sweep the ashes from the same.

7. In a gas producer the combination of a stationary ash pit, a rotating producer section 75 extending into the same, an ash plow carried by such section and serving to work the ashes onward and upward in the outer part of the pit, a shelf or scoop traveling with the producer section outside thereof, to scoop or skim off the upper part of the ashes in the pit, and a scraper past which the shelf or scoop periodically moves to throw or sweep the ashes from the same, means for hingedly mounting the scraper 85 means for yieldingly returning it to normal position and a diagonal guide to engage the free end of the scraper for the purpose specified.

In testimony whereof I have signed my 90 name to this specification in the presence of two subscribing witnesses.

WILLIAM BREWSTER CHAPMAN.
